UNITED STATES PATENT OFFICE.

LOUIS JAY GERSON, OF PALISADES, NEW YORK, ASSIGNOR OF ONE-HALF TO FRANK W. WOOD, OF NEW YORK, N. Y.

METAL KNOCKDOWN PHONOGRAPH HORN AND METHOD OF MAKING THE SAME.

1,403,314.

Specification of Letters Patent. Patented Jan. 10, 1922.

Application filed April 6, 1920. Serial No. 371,712.

To all whom it may concern:

Be it known that I, LOUIS JAY GERSON, a citizen of the United States, residing at Palisades, in the county of Rockland and State of New York, have invented certain new and useful Improvements in Metal Knockdown Phonograph Horns and Methods of Making the Same, of which the following is a specification.

10 This invention relates to phonograph horns for phonograph structures, the object thereof being to provide an improved metal horn and method of making the same, which can be readily used with a phonograph cabinet, particularly a cabinet of metal construction, such as that shown and described in my contemporaneously pending application, Ser. No. 371,711, filed April 6, 1920, the object of the present improvement being to 15 provide what may be considered a knockdown horn simple in construction, inexpensive to make and readily assembled without any bolts or similar fastening means.

In the drawings accompanying and forming a part of this specification, Fig. 1 is a perspective view of this improved horn looking toward the bottom thereof; Fig. 2 is a perspective view of the horn looking toward the top thereof; Fig. 3 is a detail view illustrating the manner of assembling the sides with the top and Fig. 4 is a sectional view taken on line 4—4 Fig. 2.

Similar characters of reference indicate corresponding parts in the several figures of the drawings.

The present improved horn is particularly adapted for use in phonograph cabinets and therefore it is shown of a form which will permit of this use, and comprises a flaring mouth and a narrow neck portion, and is made of four members, a flaring top member 2, a flaring bottom member 3, and a pair of similarly formed flaring sides 4 and 5, all formed of metal and as shown herein of sheet metal. The opposite edges of a pair of these members, shown herein as the sides, are provided with a series of projections or tongues 6 adapted to pass through openings in the other pair of members, as for instance the top and bottom members 2 and 3 adjacent to the edges thereof. These tongues are then bent over and thus secure all four members of the horn rigidly and efficiently together. The neck portion of 55 the horn is provided with outwardly turned

flanges 7 and 8. The sides 4 and 5 terminate short of the top and bottom 2 and 3, so that the flanges 8 of such sides are below the flanges 7 thereby forming a space or seat for the location of a modulating slide member shown in dotted lines at 9. The flanges 7 constitute a means for supporting and suspending the horn within the cabinet in the manner shown and described in my contemporaneously pending application. 60 The sides 2 and 3 of course are bent or flared outwardly to conform to the flare of the top and bottom.

By the present improvement I have provided a very simple metal horn, which can be shipped in the flat, that is, one plate or member upon the other since the curved form of the top and bottom is obtained during the assembling of the members by reason of the fact that in bending over the projections the top and bottom will be made to conform to the flared or tapered edges of the sides. Therefore when the flat plates are received by the dealer or user they can be easily assembled by merely slipping the 70 projections 6 through the openings and then bending them down in the manner shown.

It will be understood of course that the various details may be more or less changed without departing from the spirit or scope 75 of the present improvement, as for instance the projections could be carried if preferred by the top and bottom and the openings by the sides.

While various shapes and forms of horn 80 may be made by the present method, I have shown in the drawings, however, that form and shape of horn that is most suitable for the cabinet shown and described in my contemporaneously pending application and in 85 this form of horn, the top and bottom have greater width at the flaring mouth than the width of the sides and the top edges of the sides have greater curvature than the bottom edges thereof. In other words, in the formation of a horn having a curvature substantially resembling that shown in the drawings, the side plates 4 would be cut from the sheet of metal so as not only to have a tapered or flared formation in the 90 direction of their length but also to have curved edges whereupon when the top and bottom plates, likewise cut from the sheet of metal are assembled with the side plates, the 95 top and bottom plates will conform to the 100 105 110

curved edges of the side plates while the top plates would be cut to have sufficient flare at the mouth to enable the outer ends of the side plates to be flared outward if desired.

5 In other words, the top has greater curvature or concavity than has the bottom, and when formed of sheet metal it will be understood that the top and bottom members may be readily bent during the assemblage there-
10 of with the sides.

I claim as my invention:

1. The method of making a phonograph horn, which consists in cutting a plurality of flaring members, providing certain of
15 said members with projections along certain edges and others thereof with openings along certain edges, extending the projections through the openings and simultaneously bending certain of the members to
20 conform to the shape of the others, and bending said projections thereby to rigidly secure the members together.

2. The method of making a phonograph horn, which consists in cutting four flaring members, two thereof having greater flare
25 than the other two, and two thereof having one edge of each provided with greater curvature than its opposite edge, providing two of said members at their opposite edges with
30 projections, and two thereof with corresponding openings, then passing the projections through the openings and simultaneously bending two of the members to conform in shape to the curved edges of the
35 other two members, and then bending said projections thereby to rigidly secure the members together.

3. The method of forming a phonograph horn, which consists in cutting four flaring
40 members, two thereof having greater flare than the other two, providing two of said members at their opposite edges with projections and two thereof at their opposite edges with openings, then passing the pro-
45 jections through the openings, and then clinching said projections by bending the same upon said last mentioned members, thereby to cause two of the members to conform in shape to the flare of the other
50 two members.

4. A metal phonograph horn comprising a plurality of plates, a pair thereof having projections at the opposite edges of each, and a pair thereof having openings at the
55 opposite edges of each for the reception of said projections, said projections being bent over a pair of said plates, thereby rigidly to secure the plates together.

5. A metal phonograph horn comprising
60 four plates, a pair thereof having projections at the opposite edges of each, and a pair thereof having openings at the opposite edges of each for the reception of said projections, said projections being bent
65 over a pair of said plates, thereby rigidly to

secure the plates together, a pair of said plates also having laterally extending flanges at one end.

6. A metal phonograph horn consisting of a pair of flaring side plates having curved edges and flaring top and bottom plates having greater flare than the side plates, said plates carrying cooperating, interlocking means whereby upon assembling the same, the top and bottom plates will be bent to
75 conform to the curvature of the side plates.

7. A metal phonograph horn consisting of a pair of flaring side plates having curved edges and flaring top and bottom plates having greater flare than the side plates, the top edges of the side plates having greater curvature than the bottom edges thereof, said plates carrying detachable interlocking means whereby upon assembling the same, the top and bottom plates will be bent transversely to conform to the curvature of the edges of the side plates.

8. A metal phonograph horn comprising a plurality of plates, a pair thereof having projections at the opposite edges of each, and a pair thereof having openings at the opposite edges of each for the reception of said projections, said projections being bent over a pair of said plates, thereby rigidly to secure the plates together, a pair of said plates being shorter than another pair.

9. A metal phonograph horn comprising a plurality of flaring plates having cooperating interlocking means, a pair of said plates having less flare than the flare of a
100 companion pair, said first two plates having laterally extending flanges at one end, said last two plates terminating short of the flanged end of said first two plates.

10. A knockdown phonograph horn comprising a plurality of plates having cooperating interlocking means for assembling and detaching the plates, a pair of said plates, terminating short of a companion pair.

11. A knockdown phonograph horn comprising a plurality of plates having cooperating interlocking means for assembling and detaching the plates, a pair of said plates terminating short of a companion pair, and all having laterally extending flanges.

12. A knockdown phonograph horn comprising a plurality of plates having cooperating interlocking means for assembling and detaching the plates, and a pair thereof having a laterally extending flange adapted to 120 permit attachment to a cabinet.

13. A knockdown phonograph horn comprising a plurality of plates, some of said plates having projections along certain edges thereof and others having openings along certain edges thereof for the reception of said projections, said projections being bent to secure the plates together.

14. A metal phonograph horn comprising a plurality of plates, certain of said plates

- having projections at the opposite edges thereof and others having openings at the opposite edges thereof for the reception of said projections, said projections being bent 5 so as to secure said plates rigidly together, some of said plates having laterally extending flanges at one end.
15. A knockdown phonograph horn formed from a plurality of plates having their 10 edges connected, a pair of said plates being shorter than another pair thereby to permit the reception of a modulating slide member.
16. A knockdown phonograph horn formed from a plurality of plates having their 15 edges connected, certain of said plates being shorter than others thereof and certain of said plates having laterally formed projections to permit the detachable attachment of said horn to a phonograph cabinet.
- 20 17. A knockdown phonograph horn comprising a top and a bottom plate, and a pair of side plates, having curved edges, the construction being such that upon assembling the top and bottom plates with the side 25 plates, the same will be bent to conform to the curvature of the edges of the side plates.
18. A knockdown phonograph horn comprising a top and bottom plate, and a pair of side plates, all of said plates having cooperating 30 interlocking means, and all thereof being tapered in the direction of their length, said side plates having curved edges, whereby
- upon assembling the top and bottom plates therewith, the same will be bent to conform to the curvature of the edges of the side 35 plates, a pair of said plates terminating short of a companion pair of plates.
19. A knockdown phonograph horn comprising a top and bottom plate, and a pair of side plates, all of said plates having co- 40 operating interlocking means, and all thereof being tapered in the direction of their length, said side plates having curved edges, whereby upon assembling the top and bottom plates therewith, the same will be bent to conform to the curvature of the edges of the side plates, a pair of said plates terminating short of a companion pair of plates, and a 45 pair thereof having laterally extending projections.
20. A knockdown phonograph horn comprising top and bottom plates and a pair of side plates, all of said plates being tapered in the direction of their length, said side 50 plates having curved edges, the edges of the top and bottom plates being interlocked with the edges of the side plates and bent to conform to the shape thereof, some of said plates having at the neck portion of said horn a laterally extending flange.

Signed at New York, in the county of New York and State of New York, this third day of April, 1920.

LOUIS JAY GERSON.
